Primary Examiner — Sharon S Oum(74) *Attorney, Agent, or Firm* — John W. O'Donnell, Esq.(57) **CLAIM**

The ornamental design for a roof aperture curb with offset cleat, as shown and described.

DESCRIPTION

FIG. 1 is a bottom view of my invention;
 FIG. 2 is a top view thereof;
 FIG. 3 is a right side view thereof;
 FIG. 4 is a left side view thereof;
 FIG. 5 is a front elevational view thereof;
 FIG. 6 is a rear elevational view thereof;
 FIG. 7 is a perspective view thereof, taken from the top, front, and right side;
 FIG. 8 is a perspective view thereof, taken from the bottom, front and left side;
 FIG. 9 is a perspective view thereof, taken from the top, rear, and right side; and,
 FIG. 10 is a cross sectional view of the roof aperture curb with offset cleat thereof, taken along line 10-10 of FIG. 2.
